METHOD AND APPARATUS FOR MAKING CASTINGS

Russell J. Hines, Lakewood, Ohio, assignor to The Hines Flask Company, Cleveland, Ohio, a corporation of Ohio

Application August 11, 1955, Serial No. 527,805

5 Claims. (Cl. 22—110)

This invention relates generally to a method and apparatus for making sand molds for castings and more particularly relates to an improved method and apparatus for grouping a plurality of molds together to enable their pouring at substantially one operation.

The grouping of a plurality of sand molds together to enable their pouring at one operation will be hereinafter referred to as stack molding and envisions the stacking of molds one on top of another vertically in such a manner that the various pouring sprues of the stacked molds register with each other for simultaneous casting of a great many articles of the desired form. Preferably, the sand molds are individually formed in a separable foundry flask which is hinged at one corner and separable at another to permit removal of the flask from the corresponding sand mold.

A principal object of this invention relates to the simplification of stack molding without decreasing the efficiency or the quality of the castings.

A further object of the invention relates to an arrangement for insuring proper alignment and registration of the molds during stacking.

Briefly, in accordance with this invention, each separable foundry flask is provided with apertured lugs at opposite ends forming sockets for receiving aligning pins which assist in proper registration of the molds during stacking. The flasks are filled with sand under pressure against suitable patterns and the stack is started by placing the completed mold section onto a suitable base and then positioning vertical guide pins in the guide sockets. The vertical guide pins are preferably slotted and are fixed in position by inserting cross pins through them and then the next mold section is lowered onto the base mold section and guided into registration therewith by sliding its apertured lugs along the vertically extending guide pins in the lower mold flask. Thereafter, the cross pins are removed and the slotted guide pins are positioned upwardly through the vertical guide sockets of the surmounting mold flask into position for receiving another surmounting mold section, while at the same time releasing the lower mold flask. The lower flask is then separated from its mold and another mold flask is lowered along the guide pins onto the stack; this operation being repeated as often as necessary to build up a stack of molds of the desired number. Thereafter, the stacked molds may be poured in one operation to form a plurality of castings.

In the drawings:

Fig. 1 is a perspective view of the top mold sections in a stack with guide pins engaging both in accordance with this invention;

Fig. 2 is a perspective view of the mold sections of Fig. 1 with the guide pins displaced vertically out of engagement with the lower mold flask; and

Fig. 3 is a perspective view of the mold sections in Fig. 2 illustrating separation of the bottom flask from its mold.

Although the present invention is adapted for making a single mold cavity by superimposing a cope section over a drag section, it is primarily adapted for stack molding wherein any desired number of mold sections may be superimposed upon each other, each section being pro-

2

vided with a cope cavity on one side and a drag cavity on the opposite side so that the pair of sectional cavities can be made to register to form a complete mold cavity into which the molten metal is to be poured. Although not shown in detail, the various pouring sprues of the stacked mold sections are also made to register with one another and suitable takeoff channels leading from the pouring passage to the various cavity patterns in the stacked mold are also provided in accordance with conventional foundry practice.

As shown in the drawings, the foundry flask in which the molds are formed is preferably of the separable type having two rigidly interconnected wall halves 10 and 11 which are hinged together at one corner 12 and which carry a suitable clamp or latch 13 at the other separable corner for interlocking the two flask halves together to form an enclosed sand boundary.

Each separable foundry flask is also provided with outwardly extending U-shaped lugs 15 on opposite end walls and each lug has vertically aligned apertures 16 and 17 through its leg portions which form sockets for receiving guide pins 20 in a manner to be hereinafter more fully described.

The sand mold is formed by placing the empty flask on a pattern plate having a cope forming portion and the flask is then filled with sand in the conventional manner, except that an endless band 25 is inserted into the flask and is supported on the sand with a portion of the band projecting above the top of the flask. Thereafter, additional sand may be introduced until the band is substantially filled whereupon a presshead with a pattern plate is moved over the flask to squeeze the sand and form the mold in a manner which is described in greater detail in my co-pending application, Serial Number 491,879, filed on March 3, 1955 and entitled "Method and Apparatus of Making Molds for Casting." As a result of this operation, a smooth marginal surface is formed around the periphery of the cavity to serve as a support for the next superimposed mold section.

After a mold section A is formed, it is placed upon a suitable base board or on top of a partially formed stack of mold sections as illustrated in the drawings.

Thereafter, guide pins 20, which are longitudinally slotted from one extremity throughout the greater portion of their length to form outwardly sprung finger portions, are inserted through the guide sockets formed by the apertures 16 and 17 in each of the lugs on opposite ends of the flask. Each guide pin 20 is provided with an aperture 26 disposed transversely through the pin at the base of the slot to receive a cross pin 27 which serves to fix the guide pins 20 in their respective sockets with their slotted extremities extending beyond the upper edges of the supporting flask a distance sufficient to engage the guide sockets in another flask to be superimposed on the lower mold section. The outwardly sprung slotted extremities of the pins provide a positive engagement with the guide sockets of the upper flask and assure proper alignment.

Thereafter, another mold section B is lowered onto the lower mold section A and guided into registration therewith by sliding its apertured lugs along the vertically extending slotted extremities of the guide pins 20 carried by the lower mold section. The cross pins 27 are then removed and the guide pins 20 are easily slid vertically through the guide apertures in the upper mold section until they clear the guide sockets of the lower mold flask and occupy the same relative position in the guide sockets of the upper flask as they formerly did in the lower flask. Once the guide pins 20 are positioned in the upper flask, the cross pins 27 are again inserted to fix them in that position and the lower flask is separated and removed from its mold, after which it may be

refilled with sand and returned to a higher position in the stack. This operation may be repeated as often as desired to progressively build a stack of mold sections for the simultaneous pouring of a plurality of castings.

In this manner a plurality of separable foundry flasks may have molds formed therein and then be individually stacked by using the guide pins 20 to insure proper registration in the manner hereinbefore described, and an important feature of this invention resides in the ability to progressively build a stack of molds step by step by removing the pins from a lower flask to the next adjacent surmounting flask and then removing the lower flask for refilling and return to the stack. A stack of mold sections are thus grouped together for simultaneous pouring in one operation in a highly efficient and simplified manner. At the same time, the use of the guide pins and sockets in the step by step operation while progressively building the stack insures proper registration and alignment of the mold sections without the necessity for complex and cumbersome apparatus.

I have shown and described what I consider to be the preferred embodiment of this invention, and it will be obvious to those skilled in the art that other changes and modifications may be made without departing from the scope of my invention as defined by the appended claims.

I claim:

1. A method of stacking a plurality of separable flasks each containing a sand mold and each having apertured means forming guide sockets at opposite ends for receiving vertical guides and wherein each of said means on corresponding ends of said flasks are in generally vertically spaced relationship, comprising the steps of placing one of the flasks with its mold on a suitable base, mounting generally vertically extending guides in the guide socket at each end of the flask so that said guides project upwardly above the upper level of the flask, securing the vertical guides against downward movement by inserting a cross pin through a complementary opening in each of said guides adjacent the top of the associated of said means, aligning the guide sockets of another similar flask with the corresponding end guides of said first-mentioned flask in superimposed relationship to the latter and lowering such other flask along the vertical guides on the lower flask, removing the cross pin from each of said vertical guides, separating the guides from the lower flask by moving them upwardly through the guide sockets of the upper flask to clear the guide sockets of the lower flask and into the same relative position on the upper flask, reinserting the cross pins through the vertical guides to secure the guides against downward movement from their new location in the upper flask, and thereafter separating and removing the lower flask from its mold and repeating the foregoing operations progressively until a desired number of sand mold sections are stacked in surmounting relationship with their mold cavities aligned and registered for simultaneous pouring.

2. A foundry flask comprising, the combination of a separable boundary wall adapted to form a sand mold enclosure having spaced end walls, an outwardly projecting portion on opposite end walls, each of said portions being generally vertically spaced from the plane of the bottom of the flask and having a generally vertically disposed through aperture forming a guide socket, an elongated guide pin adapted to be slideably inserted in each socket and being movable upwardly with respect thereto and out of assembled relationship therewith, each pin having a transverse opening through its lower portion and a cross pin removably coating in said opening between the guide pin and the top of its associated socket to hold the latter pin with its free end extending upwardly beyond the top of the flask, said cross pin when in operative position engaging the top of the respective one of said portions to restrain downward axial movement of the guide pin through the socket, the free end of each guide pin being adapted to engage a corresponding socket

on a surmounting flask to guide such surmounting flask into superimposed registered relationship with the first-mentioned flask.

3. In a foundry flask in accordance with claim 2, wherein each of the guide pins is slotted generally axially throughout the greater portion of its extent to form generally outwardly spring finger sections, said finger sections insuring positive engagement with the associated guide socket of the surmounted flask to assure proper alignment of the latter with the lower flask.

4. In a separable foundry flask for producing a mold and having spaced end and side walls arranged to form a closed mold boundary hinged at one corner and separable at another corner, an outwardly extending lug on each end wall, the top and bottom surfaces of said lug being disposed respectively generally below and above the associated plane of the top and bottom of the flask, each lug having a substantially vertically disposed through aperture, a sleeve bushing in each aperture forming a guide socket on each lug, an elongated guide pin extending into each socket and having an integral base portion with a transverse opening extending therethrough and an upwardly projecting free end portion extending above the top of the flask, said pins being movable upwardly out of assembled relationship with the associated of said sockets, a cross pin removably inserted through said opening after the guide pin is seated in its socket with said cross pin being disposed above the socket and generally below the top of the mold, said cross pin being operable to restrain downward axial movement of the guide pin to thereby hold the latter with its free end extending upwardly beyond the top of the flask whereby the free end of each pin is engageable with a complementary socket in a similar surmounting flask to guide such surmounting flask into superimposed registered relationship with said first mentioned flasks, after which said guide pins are movable axially upwardly out of supported relationship with the lugs and sockets of said first mentioned flask and into supported relationship with the lugs and sockets of the superimposed flask.

5. The combination of a pair of mold flasks adapted to be assembled in multiple stacked relationship to form a complete mold cavity therebetween, each flask having walls adapted to be separable interconnected to form a closed mold boundary, each flask also having at opposite ends a vertically disposed guide socket adapted to be aligned in vertically spaced relationship with the sockets of similar flasks when the flasks are stacked on top of one another, an elongated guide pin having a base portion adapted to be inserted in each guide socket of the lower mold flask in the stack with a free extremity extending upwardly beyond the top of said lower flask and into the corresponding guide socket of the upper mold flask, thereby to establish and maintain registration between the flasks and between their mold cavities, each pin having a transverse opening in its base portion and a removable cross pin coating in said opening with the upper end of the associated socket in generally vertically spaced relationship to the confronting socket on the upper 60 of the flasks, said cross pins being operable to restrain downward axial movement of the guide pins while permitting upward axial movement, whereby upon removal of said cross pin, each of the guide pins can be moved axially and upwardly through the guide sockets until they 65 disengage from the sockets in the lower flask and occupy the same relative position in the upper flask as they formerly did in the lower flask for registration of additional mold flasks on the stack.
